CLAIM

The ornamental design for a bracket for mounting accessories over the transmission hump of a vehicle, as shown and described.

DESCRIPTION

FIG. 1 is a perspective view of a hardware mounting fixture showing my new design;

FIG. 2 is a top plan view thereof;

FIG. 3 is a side elevational view thereof;

FIG. 4 is an end elevational view thereof; and

FIG. 5 is a bottom plan view thereof.

The side and end opposite to those shown in FIGS. 3 and 4 respectively are mirror images thereof.

FIG. 1
